UNITED STATES PATENT OFFICE.

GEORGE ALIG, OF INDIANAPOLIS, INDIANA.

DESIGN FOR A COOKING-STOVE.

SPECIFICATION forming part of Design No. 31,649, dated October 10, 1899.

Application filed August 7, 1899. Serial No. 726,481. Term of patent 7 years.

To all whom it may concern:

Be it known that I, GEORGE ALIG, a citizen of the United States, residing at Indianapolis, in the county of Marion and State of Indiana, have invented and produced a certain new Design for a Cooking-Stove, of which the following is a specification.

The drawing shows a perspective view of a cooking stove or range, showing my new design.

As shown in the drawing, the leading or material features of my design consist of a body A, which rests, without feet, directly upon the floor, the fire-door B, the door C, the oven-door D, the reservoir E, and its supporting-bracket F.

The fire-door B next to the margin has an arabesque border of leaves springing from the middle of each marginal portion. This door is located opposite the end of the fire-box.

The door C is underneath the door B, below the mid-line of the side of the stove. It has three ventilating-slots near its upper end extending in a vertical direction and surrounded by a marginal convex flange. Below the slots is a shield c, outlined by a raised scroll and filled with convex ribs which taper and radiate from the bottom of the shield. In each corner of the door is a rosette, and between the two end corners is one rosette, and between the two side corners are two rosettes, and all of the rosettes on the door are surrounded by scrolls, and the blank places between the several parts of the design herein named are filled in with scrolls, as shown.

The oven-door D is rectangular in outline and has a rectangular border consisting of raised lines, the space between which is filled

in with scrolls in oppositely-curved pairs, as shown. Then touching the rectangular border at four opposite points is an oval line producing corners between the rectangles and the points of contact, which are filled with scrolls which spring from the oval line. The plain space inside of the oval line is partly filled by a convex oval ornament enough smaller to leave a plain band around it. The convex oval is ornamented by scrolls, as shown. Below the door D is the panel D' in relief and having an arabesque ornament. Between the door D and the panel D' are two rows of rivet-heads d, also two rows below the panel D' and one row across the top and down each side of the door D.

The reservoir E has the four plain straight sides e, within which and touching its inner edge at four points is a circular rib with scrolls springing from it to fill out the corners between the points of contact of the circular rib. The space inclosed by the circular rib is a plain surface, slightly convex, and at its center is secured a medallion f, of less diameter but greater convexity. It is ornamented by scrolls and a row of fleur-de-lis, as shown.

Having described my invention, what I claim as new, and wish to secure by Letters Patent, is—

The design for a cooking-stove substantially as described and shown.

In witness whereof I have hereunto set my hand and seal, at Indianapolis, Indiana, this 4th day of August, A. D. 1899.

GEORGE ALIG. [L. S.]
